ADJUSTABLE HAT SUPPORT

George A. Johnson, Crystal Falls, Mich., assignor,
by mesne assignments, of one-half to Beulah
C. Matzger

Application September 12, 1933, Serial No. 689,144

1 Claim. (Cl. 211—33)

This invention relates to certain new and useful improvements in supports, primarily designed for attractively displaying hats and the like in haberdasher and millinery stores.

5 One of the principal objects of the invention contemplates the provision and arrangement of certain adjustments for the support in order that hats and the like may be displayed at different angles suggesting the angularity at which 10 the hat may be worn and at the same time is so positioned as to be most effectively displayed by the lighting effects within a show window or case.

In the drawing:—

15 Figure 1 is a front elevation of the present invention having a hat supported thereon and tilted slightly forwardly.

Figure 2 is a side elevation illustrating a hat supported thereon in dotted lines.

20 Figure 3 is a detail sectional view taken on line 3—3 of Figure 2.

Figure 4 is a fragmentary side elevation of the invention showing the hat supporting portion of the invention provided with a straight 25 rather than an arcuate shaped edge, which configuration may be desirous when designs of head coverings are to be displayed having flatter crowns.

Referring to the drawing in detail wherein 30 like characters of reference denote corresponding parts, the reference character 10 indicates generally a base member having a standard 11 suitably connected therewith and projecting an appreciable distance therefrom in accordance 35 with the desires of the shop keeper whether the supports are to be used in show windows or upon the floors.

The hat supporting members previously referred to embody a pair of identically constructed 40 members designated by the character 12, and each of the members 12 is constructed from a thin solid piece of material having their top edges bent upon the body 12' of said members to provide these members with an upper rounded reinforced portion 13. Obviously, from the illustrations in Figures 1 and 2 of the drawing, the upper rounded 45 portions 13 engage opposite sides of the usual crease formed in soft hats, better shown in Figure 1 of the drawing.

50 The illustrations in Figures 2 and 4, showing the edges 13 of both an arcuate and straight construction, are to demonstrate that the members 12 can be so styled for supporting hats, irrespective of the particular shape and style of the crown 55 of the hat. The characters 14 and 15 denote an

inwardly offset portion formed adjacent the bottom of the body 12', and terminate in downwardly extending flat ears 16, adapted to contact with one another upon the insertion of a bolt 17 therethrough. It is, of course, to be understood that 60 the fastener 17 tends to secure the members 12 in assembled position, and due to the provision of the offsets 14 and 15, the members 12 when in hat engaging position assume an upwardly and outwardly inclined position with respect to one 65 another, forming therebetween a space suitable to accommodate the creased portion of the hat.

An adaptor member 18, which may be in the nature of a sleeve is designed to telescopically receive and frictionally engage the uppermost extremity of the standard 11 in the manner best shown in the enlarged view in Figure 3 of the drawing. Said sleeve is split longitudinally thereof in order that the component sections of the sleeve may exercise necessary tension upon 70 the standard and yet adapt itself for accommodation upon standards of different sizes. An extension 19 carried by and protruding from the sleeve is designed for overlapping relation with one of the ears 16 to accommodate a bolt member 80 20 which also passes through both of the ears 16 to adjustably accommodate a wing or butterfly nut 21 to facilitate the easy and expeditious adjustment of the hat crown engaging members so that said members can be adjusted as a unit from 85 the horizontal position shown in Figure 4 to the angular position as suggested in Figures 1 and 2.

Although I have shown and described my invention as having particular connection with the uppermost extremities of standards incident to 90 telescopic association and frictional engagement it is obviously understood that the invention may be so constructed as to readily accommodate itself upon standards or the like by providing apertured ears and screw connections between the adaptor 95 and standard without departing from the spirit of the invention.

Although I have shown and described the present invention as having particular application as a hat supporting means, for use within haberdasher and millinery shops, it is obviously understood that the invention may be equally and effectively used for many other purposes, mention of which is deemed unnecessary.

Having described the invention, what is claimed 105 is:

A hat support comprising a standard, a split sleeve frictionally engaging with the upper end of the standard, an apertured extension formed integral with said sleeve and projecting upwardly 110

above the standard, a pair of supporting members each provided adjacent their lower portion with an offset portion, apertured ears formed integral with the offset portion of the supporting members and the apertures of said ears aligning with the aperture of said extension, means passing through said ears for detachably connecting the supporting

members in oppositely inclined positions, and means passing through the aligned apertures of said extension and said ears for pivotally and detachably connecting the supporting members to said standard.
